UNITED STATES PATENT OFFICE.

BENJAMIN F. WILLIAMS, OF CHICAGO, ILLINOIS.

DRAWBRIDGE.

No. 820,687.

Specification of Letters Patent.

Patented May 15, 1906.

Application filed October 28, 1905. Serial No. 284,519.

To all whom it may concern:

Be it known that I, BENJAMIN F. WILLIAMS, a citizen of the United States, residing at Chicago, in the county of Cook and State 5 of Illinois, have invented certain new and useful Improvements in Drawbridges; and I do hereby declare the following to be a full, clear, and exact description of the invention, such as will enable others skilled in the art to 10 which it appertains to make and use the same.

My invention relates to drawbridges; and its object is to provide a bridge of this character having gates which are automatically 15 operated by the draw for closing or opening the roadway according to the position occupied by the draw.

My invention consists of hanging gates which are mounted on tracks suspended over 20 and across a roadway, and these tracks are adapted to be raised at their centers when the draw is closed, so that the gates will travel by gravity into opened position.

The invention also consists of mechanism 25 operated by the draw when open for sliding the gates together, so as to close the roadway.

The invention also consists of certain other novel features of construction and combination of parts, which will be hereinafter 30 more fully described, and pointed out in the claims.

In the accompanying drawings I have shown the preferred form of my invention.

In said drawings, Figure 1 is a central vertical longitudinal section through the draw and the adjoining portions of a bridge having my improved mechanism thereon, said draw being shown closed and the gates open. Fig. 2 is a section on line 2 2, Fig. 1. Fig. 3 40 is a view similar to Fig. 2, but showing the positions occupied by the parts when the draw is open. Fig. 4 is a bottom plan view of the gearing for manipulating the gates, the draw being shown therebetween by dotted lines; and Fig. 5 is an enlarged perspective view of the central portion of one of the gate-supporting rails and of the lifting device therefor.

Referring to the figures by numerals of reference, 1 is the draw of a bridge, the same being rotatably mounted in any desired manner and having rollers 2 at its ends adapted to travel upon abutments 3, located at opposite sides of the channel under the draw. 55 A rack 4 is secured to each end of the draw and upon the bottom thereof, and these racks

extend from points adjacent the longitudinal center of the draw toward opposite edges thereof and when the draw is closed mesh with gears 5, secured to the ends of shafts 6, 60 which extend into housings 7, located within the abutments 3 and adjacent the roadway 8. Each shaft 6 has a beveled gear 9, which meshes with oppositely-disposed gears 10, secured to shafts 11, which extend under the 65 roadway 8 to points adjacent the sides thereof, where said shafts are provided with gears 12. These last-mentioned gears mesh with gears 13, secured to shafts 14, on which are fastened gears 15, which extend slightly 70 above the road-bed at the sides thereof. The gears 15 are in alinement, and extending from the bridge at points also in alinement with the gears are standards 16, which are connected by cross-strips 17, having hangers 18 at 75 their adjoining ends and which are located above the center of the road-bed. These strips 17 are rigidly connected as by means of a bar 19, and a guide-strip 20 connects the hangers 18. Within the bar 19 and guide-strip 20 is slidably mounted a stem 21, having a T-shaped connecting-plate 22, to opposite arms of which are secured the adjoining ends of rails 23, which extend in opposite directions through slots 24 in the hangers 18 85 and are pivotally connected to the standards 16 at points below the strips 17. Mounted on each of the rails 23 are rollers 25, from which depend hangers 26, which are secured to gates 27. Pulleys 28 are mounted within 90 the lower ends of the standards 16 and support cables 29 or other like flexible devices, which are secured at one end to the outer ends of the gates 27 and have weights 30 at their other ends. Holding-plates 31 extend upward from the road-bed close to and between the gears 15, and these plates are for the purpose hereinafter more fully described. One of the arms of each connecting-plate 22 extends beyond the hangers 18, and these arms 100 are adapted, when the draw is closed, to contact with and be supported by cam-shaped lifting devices 32, which are mounted upon the ends of arms 33, extending longitudinally 105 from the centers of the ends of the draw.

It will be obvious that when the connecting-plates 22 are in position on the lifting-cams 32 the rails 23 are raised at their adjoining ends and are therefore inclined downward toward their outer ends. Weights 30, 110 therefore, pull the gates 27 down these inclined rails and in contact with the stand-

- ards 16. It will be noted that each of the gates 27 has a rack 34 secured to the bottom thereof, and when the gates are opened the inner or adjoining ends of these racks are supported in position just above but out of contact with the gears 15. When the draw is opened by any suitable mechanism provided for that purpose, the lifting-cams 32 promptly swing out of position beneath the connecting-plates 22, and said plates fall by gravity, so that the rails 23 drop to the lower ends of slots 24 and assume horizontal positions. The gates 27 will therefore drop with the rails, and their racks 34 will come into engagement with gears 15. As the draw swings its racks 4 will rotate the gears 5 meshing therewith, and motion will be transmitted from this gear through the gears 9 and 10 and shafts 11 to gears 12, 13, and 14, and all of these gears are arranged in such a manner that the two gears 15 will be caused to rotate simultaneously toward each other and will draw the racks 34 and their gates 27 into closed position. As the gates 27 come together the racks 34 thereof will become disengaged from gears 15, and the gates will assume positions upon the holding-plates 31. When the draw is closing, the racks 4 will cause the gears to rotate in opposite directions; but as gears 15 are not in mesh with racks 34 this rotation of said gears will not affect the operation of the gates and the gates will remain closed until the draw is completely closed and the lifting-cams 32 raise the connecting-plates 22. As soon as these connecting-plates are lifted by the cams the rails 23 will be inclined and the gates will be lifted off of their holding-plates 31 and will roll by gravity into opened position.
- Having thus fully described my invention, what I claim as new, and desire to secure by Letters Patent, is—
1. The combination with closures; of rails thereabove and supporting the same, said rails being pivoted at one end and vertically movable at their adjoining ends, and means operated by the draw for simultaneously raising the vertically-movable ends of the rails for directing the closures longitudinally thereon in opposite directions.
2. The combination with a draw; of supporting-rails pivoted at their opposite ends and having their adjoining ends connected and movable in a vertical plane, closures suspended from and adapted to travel upon the rails, means for engaging the closures to positively actuate them in one direction, means upon the draw for operating the actuating
- means when the draw is moving in one direction, and means upon the draw for simultaneously raising the adjoining ends of the rails to actuate the closures by gravity.
3. The combination with a draw; of a closure, mechanism operated by the opening of the draw for positively actuating the closure in one direction, and means operated by the draw for automatically moving the closure in the opposite direction upon the completion of the closing of the draw.
4. The combination with a draw; of a hanging closure, a movable track therefor, mechanism operated by the opening of the draw for positively moving the closure in one direction, and means actuated by the draw upon the completion of its closing movement for returning said closure to its initial position.
5. The combination with a draw; of a hanging closure, a movable track supporting the same, mechanism beneath and adapted to engage the closure, a rack upon the draw for actuating said mechanism when the draw is opened to move the closure in one direction, and means operated by the draw at the completion of its closing movement for automatically moving the rail to return the closure by gravity to its initial position.
6. The combination with a draw having a rack and a lifting device at one end thereof; of a hanging closure, a movable rail supporting the same, and gearing extending under the closure and adapted to move it in one direction, said gearing and rail being adapted to be operated by the rack and lifting device, respectively, for moving the closure in opposite directions.
7. The combination with a draw having a rack and a lifting device thereon; of standards, connecting means upon the standards, slotted hangers depending from said means, oppositely-extending rails movably mounted within the hangers, a connecting device interposed between the rails, hanging closures suspended from the rails, racks upon the bottoms thereof, gearing engaging and adapted to actuate the racks and their closures, said gearing and the rails being adapted to be moved by the rack and lifting device, respectively, for closing and opening the closures, respectively.
- In testimony whereof I have signed my name to this specification in the presence of two subscribing witnesses.
- BENJAMIN F. WILLIAMS.
